DAVIS

UNITED STATES PATENT OFFICE.

JOHN F. KOEPP, OF NEW KENSINGTON, PENNSYLVANIA, ASSIGNOR OF
ONE-HALF TO FRANK W. ZILLMER, OF NEW KENSINGTON, PENN-
SYLVANIA.

CURTAIN-POLE AND CURTAIN-FASTENER.

SPECIFICATION forming part of Letters Patent No. 794,414, dated July 11, 1905.

Application filed January 23, 1905. Serial No. 242,207.

To all whom it may concern:

Be it known that I, JOHN F. KOEPP, a citizen of the United States, residing at New Kensington, in the county of Westmoreland and State of Pennsylvania, have invented certain new and useful Improvements in Curtain-Poles and Curtain-Fasteners; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an improved combined curtain-pole and curtain-fastener; and it consists in forming the said pole with two grooves, the one opposite to the other and extending in the direction of its length, where-by one or more clamp members may be engaged with said grooves to attach the curtains to the pole, together with the certain details of construction and combination of parts, as will be fully described hereinafter.

In the accompanying drawings, Figure 1 is a front elevation of my improved pole and fasteners, a part of which is broken away, the said view being constructed and arranged in accordance with my invention. Fig. 2 is a perspective view of a portion of the pole and clamp member, showing the manner in which the two are engaged the one with the other, the said view being about full size. Fig. 3 is a similar view of a portion of the clamp member removed from the pole.

To put my invention into practice, I provide a pole 1, cylindrical in form and of a suitable length and diameter, and fit the ends thereof with ornamental caps 2, secured in position by split sleeves 3 in a manner that the said caps may be easily removed and replaced. This pole 1 is formed with deep grooves 5 on opposite sides and undercut to form overhanging portions 6, as will be best seen at Fig. 2 of the drawings. I now form from thin sheet metal one or more clamp members, each of which consists of the body portion 4, of a

suitable length and curved in cross-section to correspond to the curvature of the pole 1. The edges of these clamp members 4 are curled inwardly, as at 7, about a wire 8, the said wires serving the double purpose of aiding in the forming of the said portions and to strengthen, maintain, and protect the same. 50

In operation the curtains 9 are placed across the pole 1, covering the two grooves 5 and adjusted accurately in position, the clamp members 4 being removed from said pole. The clamp members 4 are now placed on the top of the curtain 9 in a position relative to the two grooves 5, the edges 7 being immediately above the overhanging portions 6. By applying pressure to the clamp member the same is forced downward and sprung into position, the curled edges 7 engaging with the projections 6, thereby locking the clamp and curtain to the pole. To remove the clamp and release the curtain, it is only necessary to disengage the cap 2 from the end of the pole and draw the said clamp endwise, the 70 same moving freely in that direction.

If it is desired, but one clamp may be used to attach the two curtains to the pole, in which case the said clamp would almost equal the length of the same; but I prefer to use two 75 or more, according to the number of curtains and the length of the pole.

Various slight modifications and changes may be made in the details of construction without departing from the spirit of the invention. Therefore I do not wish to confine myself to the exact construction shown and described, but wish to claim all such modifications as would come properly within the general scope of the invention. 80

Having thus described my invention, what I claim, and desire to secure by Letters Patent, is—

The herein-described curtain-pole and curtain-fastener, comprising the pole 1, provided with removable caps 2 at each end thereof, parallel grooves 5 on opposite sides and extending in the direction of the length of said pole, the one groove being similar to the other, 90

and undercut to form overhanging portions 6, in combination with a clamp member consisting of a thin metallic strip 4, bent in cross-section to conform with the curtain-pole, and 5 having along its edges in parallel lines, inwardly rolled or curled portions 7, each of which is provided with a wire core 8, said portions 7 adapted to enter and engage the undercuts, and clamp an interposed curtain to the

10 pole, substantially as and for the purpose described.

In testimony whereof I affix my signature in presence of two witnesses.

JOHN F. KOEPP.
